UNITED STATES PATENT OFFICE

DAVID ALAN WASHBURN, OF NEW HAVEN, CONNECTICUT

HOLDER FOR STORE WINDOW DECORATIONS

Application filed September 17, 1930. Serial No. 482,580.

The invention relates to a holder for store window decorations and is especially useful in holding any kind of paper or cloth used for decorating purposes. The invention clamps 5 paper in a flat position or holds it draped at different angles by pleating and hooking the lower ends to a clamp. The invention is simple in construction, inexpensive to manufacture and consists of a round rod fastened 10 to a floor, and so designed that paper may be held against the rod by placing the flat surface of the paper over the rod and placing a clamping device over the paper and rod. This clamp is designed so that an upward 15 extension is easily grasped by the hand and the clamp is removed by pulling the clamp upward and off the rod, thereby releasing any paper which has been clamped against the rod.

20 The invention consists of the novel arrangement of having the clamping device one piece of metal and bent so that it will fit over the rod which is fastened to the floor. By bending one of the clamping sides upward 25 and turning back the sharp upper end, a suitable handle is formed for the clasp. By placing holes along the lower surface of the handle at spaced intervals for selectively inserting a hook to which the lower part of a 30 draped store decoration has been attached, the bottom of the store decoration, whether made from paper or other material, may be held in any desired position in reference to the clamp.

35 In the drawings:

Fig. 1 is an end view of the device attached to the floor.

Fig. 2 is a top view of the rod showing the manner of attaching the same to the floor.

40 Fig. 3 is a side view of Fig. 2 showing more detail.

Fig. 4 is a perspective view of Fig. 1.

In the preferred form of the invention as 45 illustrated by the drawings, at spaced intervals along the length of a round rod 6 a small section 10 is filed off and a hole bored through this filed off section of the rod through which a screw 11 is inserted for holding the rod 6 to the floor, as shown in Figure 3. The screw 50 through each filed off section 10 will not inter-

fere in any way with the clamp 3 which fastens over the rod 6 by means of friction because the screw head will not extend above or beyond the filed off section 10 due to the shape of the upper part of the screw hole corresponding in size to the head of the screw. This arrangement allows paper to be clamped against the rod 6 by means of the clamp 3 so that each screw 11 which holds the rod 6 to the floor will not in any way tear or injure the paper so held. The bottom part of the clamp 3 is bent in the shape of a U which corresponds in size along its entire length to the rod 6 over which it fits. When pushed against the rod 6 the U shaped clamp has sufficient flexibility to fit over the rod 6 and is held by friction until removed. Above the upper side of the clamp 3 and under the handle 12 there are a plurality of holes 2 spaced at equal intervals and in corresponding positions in reference to handle 12. When one hook attached to a window decoration, as shown in Figure 4 is also inserted through a selected hole 2, the lower part of a window 60 decoration is held in any desired position or angle. The clamp may be placed on the rod or removed at will without any injury to cloth or paper, or any other material which is held in any position against the rod 6 by the U shaped clamp 3.

65 The clamp 3 is made from a single piece of flat material which has a certain amount of flexibility, and has its lower section rounded to correspond more or less in size to the rod 6. By exerting force on the upper side of the clamp the lower rounded side will fit over the rod 6 and be held by friction. One side of the U shaped clamp 3 is bent up so as to form a convenient handle 12 by having its 70 upper part, as shown in Figure 1, bent around so as to avoid sharp edges. Just below the upper rounded part 12 of the clamp but above the U shaped section 3 of clamping device, a series of holes are inserted at spaced intervals along the entire length of a section 7 shown in Figure 4. This design allows the 75 whole clamping section to be made from a single piece of sheet metal.

80 My invention for holding crepe paper used in decorating store windows makes it pos- 85

sible to hold either or both ends of paper in a flat position against the rod 6 by inserting the clamp 3 over the rod, or the same device can hold one end of paper in a position which 5 is not flat. This is accomplished by drawing the bottom ends of the paper I together by means of inserting a hook 8, shown in Fig. 1 through the bottom of the paper and inserting the other end of the hook 8 through any 10 one of the holes 2 shown in Fig. 4 thereby positioning the store decorations at any desired angle according to any selected hole 2 into which the other end of hook 8 is inserted.

I do not limit myself to using my invention 15 in connection with store windows, or for only paper decorations, as it may be used for holding curtains or other material in any way consistent with the claims.

What I claim:

20. 1. A holder for store decorations consisting of a clamp made from one piece of flat metal, bent so that its lower end is U shaped and releasably held over a round rod attached to a smooth surface, one side of said lower 25 end is bent up to form a handle and curtain hooks releasably attached through a selectively located hole through said bent piece of metal.
2. A clamp for window decorations, consisting of a clamping device which is held by friction to a rod attached to the floor by means of screws passing through cut out sections of the said rod; said clamp having a handle under which holes are spaced at equal 35 intervals, said holes having a hook through each of them, said hooks selectively attached to a decoration.
3. A store window decoration holder consisting of a round rod having one or more sections filed off and having a hole through each section corresponding in size to a screw passing through said hole and attaching said rod to any surface; a clamp equal in length to the length of the rod and having its lower section of a corresponding size and shape to the diameter of the rod and its upper section forming a handle; said device having a hole under the handle through which hooks are inserted, and means for attaching paper decorations under the clamping device or to any hook.

In testimony whereof I affix my signature.

DAVID ALAN WASHBURN.
